FLUID PRESSURE CONTROL APPARATUS FOR FREE PISTON MACHINES

Original Filed July 22, 1947

UNITED STATES PATENT OFFICE

2,661,020

FLUID PRESSURE CONTROL APPARATUS
FOR FREE PISTON MACHINES

Arthur J. Bent, Penn Township, Allegheny County, Pa., assignor to Westinghouse Air Brake Company, a corporation of Pennsylvania

Original application July 22, 1947, Serial No. 762,771, now Patent No. 2,608,052, dated August 26, 1952. Divided and this application June 15, 1948, Serial No. 33,044

8 Claims. (Cl. 137—656)

1

This invention relates to control apparatus for free piston machines, particularly of the gas generator type, embodying two oppositely arranged motor operated air compressor portions each embodying an internal combustion operated power piston and a coaxially arranged and rigidly connected air compressor piston operative by said power piston to compress air for scavenging and feed of the motor part of the machine and in which the mixture of the hot gases of combustion and of the excess of scavenger air discharged from the motor part of the machine in form together generated motive gas which may be employed to perform mechanical work as by expansion in a turbine, the present application being a division of my copending application Serial No. 762,771, filed July 22, 1947, now Patent No. 2,608,052, issued August 26, 1952.

In Patent No. 2,406,037 issued on August 20, 1946, to R. P. Ramsey there is disclosed a free piston machine of this general type which embodies two oppositely and coaxially arranged motor compressor units each embodying a piston assembly comprising a power piston, an air compressor piston and a direct bounce piston. Between the two power pistons is a power or combustion chamber into which fuel is adapted to be injected for compression ignition for driving said pistons apart. At the outer face of each air compressor piston is an air compressing chamber and said piston is operative by the respective power piston to compress air from said chamber into a scavenger receiver for the purpose above set forth. At the outer face of each direct bounce piston is what may be called a direct bounce chamber in which air is adapted to be compressed upon the air compressing stroke of the respective power piston to provide energy for returning the piston assembly, following scavenging, to its inner position preceding another power stroke. The amount of air necessary in the direct bounce chambers for accomplishing the result just mentioned, as well as for limiting the outward stroke of the piston assemblies in case of variation in fuel supply to the combustion chamber, must be varied in accordance with the pressure in the scavenger receiver which acts on the air compressing pistons in the same direction as that in the direct bounce chambers at the end of the air compressing stroke, and which at the termination of scavenging the combustion chamber acts therein on the power pistons in opposition to pressure of air in the direct bounce chambers and the principal object of the invention is the provision of improved means in the form of a direct

2

bounce governor device controlled by pressure of air in the scavenger receiver and the stroke of the piston assemblies for automatically so regulating the amount of air in the direct bounce chambers.

Other objects and advantages will appear from the following more detailed description of the invention. In the accompanying drawing the single figure is a diagrammatic, sectional view of a direct bounce governor device embodying the invention.

DESCRIPTION

As shown in the drawing, the direct bounce governor device comprises a fluid pressure regulating mechanism 350 for controlling the pressure of fluid in the direct bounce chambers of a free piston gas generator (not shown) and a control portion 351 for controlling operation of said regulating mechanism, said mechanism and control portion comprising a common casing section 352 mounted on a pipe bracket 353 and the said mechanism comprising in addition a casing section 354a mounted on the casing section 352.

The fluid pressure regulating mechanism 350 comprises a supply valve 355 contained in a chamber 356 and arranged to cooperate with a seat 357 for controlling flow of fluid under pressure from chamber 356 to an outlet chamber 358 provided in bracket 353. A guide member 359 projecting above the seat 357 is provided with a tapered opening for receiving the valve 355 to guide it to its seat and to also cooperate with said valve when in said opening to throttle flow of fluid under pressure from chamber 356 to the outlet chamber 358. The chamber 356 is adapted to be constantly supplied via a pipe 354 with fluid under pressure from any suitable source. The outlet chamber 358 is open to a pipe 330 adapted to be connected to the direct bounce chambers in the free piston gas generator (not shown).

The supply valve 355 is connected to the end of a stem 361 by a pin 362, said stem projecting from a control piston 363 operatively mounted in a bushing 364 held in position between the casing sections 352 and 354a. An equalizing port 365 through the bushing 364 is provided to permit equalization of fluid pressure from chamber 356 into a chamber 366 at the stem side of the piston 363. At the opposite side of the piston 363 is a control chamber 367 open through a choke 368, a strainer 369 and a passage 369a in the piston stem 361 to chamber 356. A spring follower 356a mounted on the stem 361 in contact with valve 355 is engaged by one end of a precompressed spring 368a the other end of which is supported by the bushing 364, said spring being

provided for closing said valve upon substantial equalization of pressure of fluid acting on opposite sides of piston 363.

Disposed in the casing section 354a is a valve seat member 370 held in place by a retainer 371 secured in said casing section. The seat member 370 has a bore open at one end to a passage 372 leading to the outlet chamber 353 and to the control portion 351 of the direct bounce governor device. The opposite end of this bore opens through a valve seat 373 to a chamber 374 which in turn is connected through one or more ports 375 in retainer 371 to the control chamber 367 at the one face of piston 363. Slidably mounted in a bore in the retainer 371 coaxially of the valve seat 373 is a valve 376 arranged to cooperate with seat 373 for closing communication between chamber 374 and passage 372. A plunger 377 slidably mounted in a bore in a partition wall 378 has an extension 379 of smaller diameter than the axial bore in seat member 370 and extending therethrough for contact with the valve 376 for unseating it against a spring 380 carried by the retainer 371. The plunger 377 is provided on its opposite end with a projection 382 extending into a chamber 384 for cooperation with a valve 383 which is slidably mounted in a bore 384 arranged in coaxial relation to said plunger 377 in an element 385 secured in the casing. The valve 383 may be provided with slots 386 around its edge to provide communication between opposite sides thereof. The chamber 384 is open through a port 387 to passage 372 and thereby to the outlet chamber 353.

A cover 388 is clamped to the end of the casing section 354a opposite that engaging the casing portion 352, and clamped between said cover and the casing section 354a is a flexible diaphragm 389 arranged in coaxial relation with the bore 384 in the element 385. At one side of this diaphragm is a control chamber 390 in which the element 385 is disposed. At the opposite side of the diaphragm is another control chamber 391. The chamber 390 is open through a passage 392 to a pipe 393 adapted to be connected directly to one of the direct bounce chambers in the gas generator (not shown), a chosen restriction to flow of air through this communication being provided as by said pipe being of relatively small flow capacity. The chamber 391 is open through a choke 394 and a passage 395 directly to the fluid pressure supply pipe 354.

A diaphragm follower 396 disposed in chamber 390 engages the adjacent face of diaphragm 389 and has a portion 397 extending through a central opening in said diaphragm and a follower 398 disposed in chamber 391 against the opposite side of the diaphragm, and these followers are rigidly clamped to opposite sides of said diaphragm by a securing element 399 engaging the follower 398 and having internal screw-threaded engagement with the portion 397 of the follower 396.

The diaphragm follower 396 has an integral member 400 disposed in the bore 384 in the element 385, said member 400 having a spherical like surface in sliding contact with the wall of said bore and carrying a sealing ring 401 having sealing contact with said wall. On the innermost end of the integral member 400 is formed a valve seat 402 arranged for sealing engagement with the valve 383. A shoulder 403 substantially encircling the valve seat 402 and projecting from the wall of bore 384 is provided for contact by valve 383 for unseating said valve from the mem-

ber 400 upon movement of said member in the direction away from said valve.

The valve seat 402 encircles a fluid pressure release passage 404 extending through the integral member 400 and the follower 396 to a chamber 405 provided at the opposite side of the diaphragm 389 in a coaxially arranged cylindrical portion 406 of the securing element 399. Slidably mounted in the cylindrical portion 406 is one end of a rigid strut 407 the opposite end of which is slidably mounted in a bore in the casing cover 388, which bore is normally in coaxial relation with the cylindrical portion 406. The strut 407 has an axial bore 408 establishing communication between chamber 405 and a passage 409 in the casing cover 388 which passage opens to atmosphere. The opposite end portions of the strut 407 in contact with the wall of the bore in the casing cover 388 and with the wall of the cylindrical portion 406 are rounded to permit free slight misalignments or wobbling of the diaphragm 389 during movement thereof, which will be later described, and in each end of said strut is a sealing ring 410 having sealing and sliding contact with the respective wall for preventing leakage of fluid under pressure from the control chamber 391 to the atmospheric passage 409.

The diameter of the rigid strut 407 at its point of contact with the cylindrical portion 406 of the securing element 399 is greater than the diameter of the integral member 400 at the opposite side of the diaphragm which is disposed in the bore 384, whereby less area of the diaphragm 389 is subject to pressure of fluid in chamber 391 than is subject to opposing pressure of fluid in chamber 390, in order that a lower pressure of fluid in the latter chamber will provide a force to balance a higher pressure of fluid in the former chamber during operation, to be hereinafter described.

The control portion 351 of the direct bounce governor device comprises a flexible diaphragm 411 secured around its edge between the casing section 351 and the cover 412. Between the cover 412 and the diaphragm 411 is a control chamber 413 open through a passage 414 to a pipe 415 adapted to be connected to the scavenger air receiver of the free piston generator (not shown). At the opposite side of diaphragm 411 is a chamber 416 which is open to atmosphere through a vent port 417.

A follower 418 disposed in chamber 413 against the adjacent face of diaphragm 411 has a stud portion 419 extending centrally through the diaphragm into chamber 413 and over this stud portion in the latter chamber is mounted a follower plate 420 against the diaphragm and a nut 421 having screw-threaded engagement with said stud portion for clamping the central portion of the diaphragm between the follower 418 and plate 420. A regulating spring 422 contained in chamber 416 and supported at one end on the casing section 352 bears against the diaphragm follower 418 urging the diaphragm 411 in the direction of cover 412.

The casing section 352 has a bore arranged in coaxial relation with the diaphragm 411 and containing a plunger 423. The plunger 423 is provided on the end adjacent the diaphragm 411 with a stem 424 extending through a chamber 425 and an axial bore in a bushing 426 secured in the casing section 352, into chamber 416 and thence through said chamber into contact with the diaphragm follower 418. Adjacent to the 75 follower 418a washer 427 is secured to plunger

stem 424 by a ring 428 secured to said stem and interposed between one side of this washer and a shoulder in the casing section 352 is a bias spring 429 for maintaining the stem 424 in constant contact with the diaphragm follower 418. The chamber 425, it will be noted, is formed between one end of the plunger 423 and the adjacent end of bushing 426. A sealing ring 430 carried by the bushing 426 has sealing contact with the wall of the casing section 352 in which said bushing is mounted for preventing leakage of fluid under pressure from chamber 425 past said bushing to the atmospheric chamber 416. Another sealing ring 431 carried by bushing 426 has sealing and sliding contact with the stem 424 to prevent leakage of fluid under pressure from chamber 423 along said stem to atmospheric chamber 416.

The plunger 423 has a bore 432 closed at the end adjacent stem 424 and opening at the opposite end to one end of a supply valve chamber 433 the other end of which is closed by plug 434 secured by a ring 435 in the end of said plunger opposite the end from which projects the stem 424. The plug 434 is provided in valve chamber 433 with an annular valve seat 436 arranged for sealing contact by a disc valve 437 contained in said chamber. A spring 438 extending through the bore 432 and chamber 433 acts on the valve 437 for urging it toward seat 436.

The end of the portion of plunger 423 containing the plug 434 is disposed in a chamber 439 and said chamber and chamber 425 at the opposite end of the plunger are both connected to passage 372 from the outlet chamber 358. Midway between its ends the plunger 423 is provided with an annular cavity 440 formed in its outer surface and open by way of a passage 441 to the diaphragm chamber 391 in the fluid pressure regulating mechanism 350. The plunger 423 is further provided with one or more ports 442 opening the annular cavity 440 to bore 432 within said plunger. At either side of cavity 440 the plunger 423 is provided with an annular sealing ring 443 having sealing and sliding contact with the wall of the bore in the casing section in which said plunger is mounted for preventing leakage of fluid under pressure between said cavity and chambers 425 and 439 at opposite ends of the plunger. A similar ring 463a carried by the plug 434 and engaging the wall of the bore in plunger 423 in which said plug is disposed is provided to prevent leakage of fluid under pressure from chamber 433 to chamber 439.

The valve seat 436 encircles an axial bore 444a extending through the plug 434 and opening to chamber 439, and freely extending through said chamber and bore into contact with the valve 437 is one end of a plunger 444 which is carried by a housing 445 secured to the casing section 352. The plunger 444 comprises an enlarged central portion 446 slidably mounted in a suitable bore in the housing 445. Extending from one end of the central portion 446 through a chamber 447 in said housing and thence through a partition wall 448a separating said chamber from chamber 439 is a portion 448 of reduced section from the end of which projects a portion 449 which engages the valve 437, the portion 449 being of smaller diameter than that of bore 444a through plug 434 to provide for flow of fluid under pressure through said bore. The chamber 447 is open to atmosphere as by way of a vent port 449a. Projecting from the opposite end of

the central portion 446 of the plunger is a portion 450 of smaller cross-sectional area than the central portion. The portion 450 is slidably mounted in a suitable bore provided in a plug 451 secured in the housing 445 by a ring 452, and extends beyond the outer end of the plug 451 and of the housing 445. At the inner end of plug 451 is a chamber 453 encircling the portion 450 of plunger 444 and connected by a passage 454 to the annular cavity 440 and thence by way of passage 441 to diaphragm chamber 391 in the fluid pressure regulating mechanism 350.

A sealing ring 455 carried by the plug 451 has sealing contact with the encircling housing 445 for preventing leakage of fluid under pressure from chamber 453 past said plug to atmosphere. Another sealing ring 456 carried by plug 451 has sealing and sliding contact with the portion 450 of the plunger 444 for preventing leakage of fluid under pressure from chamber 453 along said portion of the plunger to atmosphere. A sealing ring 457 carried by the housing 445 has sealing and sliding contact with the peripheral surface of the central portion 446 of the plunger 444 for preventing leakage of fluid under pressure from chamber 453 to the atmospheric chamber 441, and another sealing ring 458 carried by said housing has sealing and sliding contact with the peripheral surface of the portion 448 of said plunger for preventing leakage of fluid under pressure from chamber 439 to the atmospheric chamber 441.

It will be noted that when fluid under pressure is present in chamber 453 it will act over the area of the central portion 446 of the plunger 444 encircling the portion 450 and produce a force which will urge said plunger in the direction of valve 437. This force however is opposed by pressure of fluid in chamber 439 acting on the exposed end surface of plunger 444 and the differential between these two opposing forces is such as to constantly urge the plunger 444 against the valve 437, but is insufficient to ever unseat the valve 437 against the greater opposing pressure on said valve of spring 438.

A tappet 22 is provided to engage plunger 450 for operating same to unseat the valve 437 from its seat 436. The tappet 22 may be associated with one of the piston assemblies of the gas generator (not shown) and be arranged to thus unseat the valve 437 when said assembly tends to move beyond its inner dead center position on its air intake stroke. During operation of the generator it will therefore be seen that the valve 437 will momentarily be opened during each cycle of operation of the generator.

OPERATION

In operation, assume that pipe 354 is supplied with fluid under pressure. From pipe 354 such fluid will then flow into the supply valve chamber 356 and also through passage 395 and choke 394 into diaphragm chamber 391 and from the latter chamber through passage 441 and ports 442 in the plunger 423 to the valve chamber 433 in said plunger.

Now assuming that valve 437 is seated with diaphragm 411 and plunger 423 in the position in which they are shown in the drawing and which position will be assumed when the pressure in diaphragm chamber 413 and in the scavenger receiver (not shown) is substantially that of atmosphere, as before mentioned, the pressure in diaphragm chamber 391 of the fluid pressure regulating mechanism 350 will gradually increase

7 through choke 394 and provide a force on diaphragm 389 which will move same in the direction of chamber 390 for thereby actuating the integral member 400 into seating engagement with the valve 383 and for then shifting said valve against plunger 377 to unseat the valve 376. Upon unseating of valve 376 the chamber 367 at one side of the control piston 363 will be opened past said valve to passage 372 and thence to the outlet chamber 358 which may be open to the direct bounce chambers in the gas generator (not shown). The pressure in the supply piston chamber 387 will thereby be reduced sufficiently below the supply pressure in chamber 386 to provide a force on the piston 363 to move same in a direction to pull the supply valve 355 away from the seat 357, whereupon fluid under pressure from the supply valve chamber 356 will flow to the outlet chamber 358 and thence to the direct bounce chambers in the gas generator.

As fluid under pressure is thus supplied to the direct bounce chambers in the gas generator (not shown) it will equalize through pipe 393 back into diaphragm chamber 398 in the direct bounce governor device and thereby provide a force on diaphragm 389 opposing pressure of fluid in chamber 391. Since the area of diaphragm 389 subject to pressure of fluid in chamber 390 is greater than that subject to pressure of fluid in chamber 391, it will be seen that when the pressure in the former chamber becomes increased to a degree somewhat less than that acting in chamber 391 said diaphragm will deflect in the direction of the left hand to permit closing of valve 376 by spring 390.

When the valve 376 in the direct bounce governor device is closed as just described, fluid at the supply pressure in chambers 366, 356 at one side of piston 363 will promptly equalize through the passage 369a and choke 368 into piston chamber 367 whereupon spring 368a will actuate said piston to close the valve 355 for preventing further flow of fluid under pressure to the outlet chamber 358 and thereby to the direct bounce chambers in the gas generator and back to chamber 390.

Now let it be assumed that the tappet 22 is periodically operated to unseat the valve 437, assuming the diaphragm 411 and valve seat 436 to be in the position in which they are shown in the drawing. This periodic unseating of valve 437 will release fluid under pressure from chamber 391 to chamber 358 which is at lower pressure. The venting capacity of valve 437 is so in excess of the flow capacity of choke 394 to supply fluid under pressure to chamber 391 that the pressure in said chamber will become reduced by the periodic unseating movements of valve 437 and hence permit pressure of fluid in chamber 398 to deflect the diaphragm 389 in the direction of the lower pressure in chamber 391, such movement unseating the release valve 383 to permit release of fluid under pressure from chamber 358 and the connected chamber 390. When the pressure in chamber 390 thus becomes reduced sufficiently pressure of fluid in chamber 391 will deflect diaphragm 389 to close the release valve 383 for thereby limiting the pressure in chamber 390 to substantially the reduced degree acting in chamber 391.

Now assume that by increasing pressure of fluid in chamber 413 the diaphragm 411 is correspondingly deflected against spring 422. The valve seat 436 will be correspondingly displaced and assuming that reciprocation of tappet 22 is not changed,

8 the length of time which the valve 437 will be unseated for each movement of said tappet will be correspondingly greater resulting in a corresponding further reduction in pressure in chamber 391 and thereby operation of diaphragm 389 to open the release valve 383 to cause a like reduction in pressure in chamber 390. The pressure in chamber 390 will thus be reduced in accordance with the increase in pressure in chamber 413 on diaphragm 411 due to the proportionally increased time which the valve 437 is off its seat 436. On the other hand, if the pressure of fluid in chamber 413 is reduced the seat 436 will be moved closer to valve 437 so that the length of time which said valve will be off its seat during reciprocation of tappet 22 will be correspondingly reduced. As a result the pressure in chamber 391 will be increased by the supply through choke 394 relative to the pressure acting in chamber 390 and thereby cause deflection of diaphragm 389 to open the supply pilot valve 376. As before described, piston 363 will then open the supply valve 355 to increase the pressure of fluid in chamber 358 and thereby in chamber 390 correspondingly, whereupon the diaphragm 389 will be deflected by fluid in the latter chamber to permit seating of the supply pilot valve 376 and thereby closing of the supply valve to prevent further supply of fluid under pressure to chamber 358.

If the length of stroke of tappet 22 is increased the same result will occur as in case of increasing pressure of fluid in chamber 413, while if the length of said stroke is shortened the pressure in chamber 358 will be increased the same as if pressure of fluid in chamber 413 is reduced.

It will therefore be seen that the fluid pressure regulating mechanism 350 will operate to vary the pressure of fluid in chamber 358 in accordance with operation of the control portion 351 of the governor as controlled by pressure of fluid in chamber 413 and the length of reciprocating stroke of tappet 22. As applied to a free piston gas generator where chambers 358 and 390 are open to the direct bounce chambers, chamber 413 is open to the scavenger receiver for subjecting diaphragm 411 to pressure of fluid delivered by said generator, and tappet 22 is arranged for reciprocation by the generator pistons near the end of their inward stroke, the direct bounce governor device will therefore automatically vary the amount of fluid under pressure in the direct bounce chamber of the generator as necessary to maintain a desired stroking of the generator pistons.

Having now described my invention, what I claim as new and desire to secure by Letters Patent, is:

1. A valve device for governing the quantity of fluid under pressure in a chamber comprising a casing, a supply valve cooperative with a seat in said casing for controlling supply of fluid under pressure to said chamber, a release valve slidable in a bore in said casing in coaxial relation to said supply valve, means connecting said valves for movement in unison, seating means for urging said supply valve to its seat, a flexible diaphragm in said casing arranged in coaxial relation to said valves and subject on one side to a variable control fluid pressure in a control chamber, follower means secured centrally to and movable with said diaphragm, seat means for said release valve movable with said follower means and disposed in said bore in sliding and sealing contact with the wall thereof, said follower means having a

cavity and a passage connecting said cavity to said seat means, said release valve controlling communication between the first named chamber and said passage, conduit means connecting said cavity with an atmospheric opening in said casing, and means subjecting the opposite side of said diaphragm to pressure of fluid from the first named chamber which opposes pressure of fluid acting on said diaphragm in said control chamber, said diaphragm being operative upon a preponderance in pressure in said control chamber over the opposing pressure of fluid to seat said release valve and open said supply valve and upon a preponderance in said opposing pressure of fluid over that in said control chamber to move said seat means out of seating cooperation with said release valve and to permit seating of said supply valve by said seating means.

2. A valve device for governing the quantity of fluid under pressure in a chamber comprising a casing, a supply valve cooperative with a seat in said casing for controlling supply of fluid under pressure to said chamber, a release valve slideable in a bore in said casing in coaxial relation to said supply valve, means connecting said valves for movement in unison, seating means for urging said supply valve to its seat, a flexible diaphragm in said casing arranged in coaxial relation to said valves, follower means secured centrally to and movable with said diaphragm, seat means for said release valve movable with said follower means and disposed in said bore in sliding and sealing contact with the wall thereof, said follower means having a cavity and a passage connecting said cavity to said seat means, said release valve controlling communication between said chamber and said passage, conduit means extending through a fluid pressure control chamber at one side of said diaphragm connecting said cavity to an atmospheric opening in said casing, means subjecting the opposite side of said diaphragm to pressure of fluid from the first named chamber which opposes pressure of fluid acting on said diaphragm in said control chamber, said diaphragm being operative upon a preponderance in pressure in said control chamber over the opposing pressure of fluid to seat said release valve and open said supply valve and upon a preponderance in said opposing pressure of fluid over that in said control chamber to move said seat means out of seating cooperation with said release valve and to permit seating of the supply valve by said seating means, choke means providing a constant controlled rate of supply of fluid under pressure to said control chamber, variable operable means for releasing fluid under pressure from said control chamber and automatically operative variable stroke means for controlling operation of said variable operable means to thereby vary the rate of release of fluid under pressure from said control chamber with respect to the constant rate of supply to thereby regulate pressure of fluid in said control chamber.

3. A valve device for governing the quantity of fluid under pressure in a chamber comprising a supply valve for supplying fluid under pressure from a source to said chamber, a piston connected to said valve and subject on one side to pressure of fluid in said source and on the opposite side to pressure of control fluid in a control chamber, and operative upon a reduction in the latter pressure to open said supply valve, a restricted passage connecting opposite sides of said piston for equalizing the fluid pressures on said opposite sides, spring means for closing said supply valve

upon equalization of fluid pressures on said opposite sides, a supply pilot valve for releasing fluid under pressure from said control chamber to the first named chamber, a release valve arranged in coaxial relation to said supply pilot valve for releasing fluid under pressure from said first named chamber, movable abutment means subject to fluid under pressure from said first named chamber and to an opposing variable control fluid pressure in a second control chamber, and means operable by said abutment means upon a preponderance in pressure in said second control chamber over the opposing fluid pressure to close said release valve and open said supply pilot valve and upon a preponderance in pressure from said first named chamber over that in said second control chamber to effect closing of said supply pilot valve and opening of said release valve.

4. A valve device comprising means providing a constant flow of fluid under pressure to a control chamber, a fluid pressure release passageway connected to said chamber, cooperating valve and valve seat elements controlling communication through said passageway for releasing fluid under pressure from said chamber to provide a pressure therein corresponding to the length of time said elements are unseated one from the other, pressure means responsive to variations of pressure of fluid for accordingly positioning one of said elements, and reciprocating means for intermittently unseating the other element from said one element.

5. A valve device comprising means providing a constant flow of fluid under pressure to a chamber, cooperating valve and valve seat elements controlling a communication connected to said chamber for releasing fluid under pressure from said chamber to provide a pressure therein corresponding to the length of time said elements are unseated one from the other, a regulating spring, a movable abutment subject to pressure of said regulating spring and opposing pressure of fluid adjustable to a position corresponding to the pressure of such fluid, means connecting one of said elements for adjustment by said abutment, and operating means for intermittently moving the other valve element out of seating contact with said one valve element.

6. In combination, valve means for selectively supplying fluid under pressure to and releasing fluid under pressure from a chamber, movable abutment means controlled by opposing pressures of fluid in a first chamber and in a second chamber which is adapted to be open to the first named chamber, and operative upon a preponderance in pressure in said first chamber over that in said second chamber to effect operation of said valve means to supply fluid under pressure to the first named chamber and upon a preponderance in pressure in said second chamber over that in said first chamber to effect operation of said valve means to release fluid under pressure from the first named chamber, fluid pressure adjustable means and reciprocable means cooperable with said fluid pressure adjustable means for controlling pressure of fluid in said first chamber.

7. In combination, valve means for selectively supplying fluid under pressure to and releasing fluid under pressure from a chamber, movable abutment means controlled by opposing pressures of fluid in a first chamber and in a second chamber which is adapted to be open to the first named chamber, and operative upon a preponderance in pressure in said first chamber over that in said second chamber to effect operation of said valve

11

means to supply fluid under pressure to the first named chamber and upon a preponderance in pressure in said second chamber over that in said first chamber to effect operation of said valve means to release fluid under pressure from the first named chamber, relatively movable valve and valve seat elements cooperative to vary pressure of fluid in said first chamber according to extent of movement of one of said elements relative to the other, fluid pressure adjustable means for positioning said other element in accordance with the pressure of such fluid, and reciprocable means for periodically moving said one element relative to said other element.

8. In combination, valve means for selectively supplying fluid under pressure to and releasing fluid under pressure from a chamber, movable abutment means controlled by opposing pressures of fluid in a first chamber and in a second chamber which is adapted to be open to the first named chamber, and operative upon a preponderance in pressure in said first chamber over that in said second chamber to effect operation of said valve means to supply fluid under pressure to the first named chamber and upon a preponderance in
